UNITED STATES PATENT OFFICE.

ISIDORE ROTHSTEIN, OF PITTSBURGH, PENNSYLVANIA.

GAME APPARATUS.

1,090,653.

Specification of Letters Patent. Patented Mar. 17, 1914.

Application filed September 9, 1912. Serial No. 719,285.

To all whom it may concern:

Be it known that I, ISIDORE ROTHSTEIN, a resident of Pittsburgh, in the county of Allegheny and State of Pennsylvania, have invented a new and useful Improvement in Game Apparatus; and I do hereby declare the following to be a full, clear, and exact description thereof.

My invention relates to games and has special reference to the class of games as are usually played by children at parties, entertainments, etc.

The object of my invention is to provide a cheap, simple and convenient form of a game which can be played by two or more persons, in which a representation of a flag or other emblematic design will be formed during the course and at the end of the playing, and will provide such a form of game which will be instructive and amusing.

To these ends my invention consists, generally stated, in the novel arrangement, construction and combination of parts, as hereinafter more specifically set forth and described and particularly pointed out in the claims.

To enable others skilled in the art to which my invention appertains to construct and use my improved game, I will describe the same more fully, referring to the accompanying drawing, in which:

Figure 1 is a view of my improved game as formed. Fig. 2 is a view showing one of the stars used in playing the game.

Like symbols of reference herein indicate like parts in each of the figures of the drawing.

As illustrated in the drawing 1 represents a sheet of suitable material, such as a fabric formed from muslin, linen, bunting, etc., which sheet is of rectangular shape and is to form the representation of the United States flag, as hereinafter described. The sheet 1 has a body or flag portion 2 and a lower or sub portion 2' connected to the bottom of said flag portion and forming part of the same.

At the upper left hand corner of the flag portion 2 is a blue colored field 3, which extends from the upper and left hand edges of the sheet 1 into said portion, and extending out from the right hand side of said field and under the same from said left hand edge are a series of alternate white and red colored stripes 4 and 4' respectively, ex-

tending to the right hand edge of said sheet. Within the center of the field 3 is a single white star 5 to represent the District of Columbia as containing the capital of the United States of America, and such field, 60 stars and stripes 4 and 4' can be formed in the flag portion 2 in the usual or any suitable manner, such as by stamping or printing such parts in the flag portion 2 or by stitching the same together to form such 65 portion. The lower portion 2' of the sheet 1 is preferably blue colored, having within the same white stars 6 to the number of forty-eight, to represent the number of 70 States within the United States of America, and such stars are preferably arranged in vertical lines of four each and formed within such portion, as well as such portion, in the usual or any suitable manner, such as by 75 stamping, printing or stitching the same together to form said portion.

The manner of using and playing my improved games is as follows:—The sheet 1 as thus formed is placed against the wall or other suitable place and secured in position in any suitable manner, and either before or after it is in position, the base portion 2' can be removed or the stars 6 removed therefrom by cutting or in any suitable manner. The persons who desire to 80 play the game are blindfolded and each take one of the stars 6 and endeavor to place such stars by pinning the same on the field 3 of the body portion 2 and as close to the single star 5 in such field as they can guess so 85 that the person or persons having their star 6 within said field and closest to the star 5 therein will be counted the winner of the game after all of such stars 6 are placed on said portion in endeavoring to represent 90 the flag of the country of the United States of America, and such stars 6 representing all the States of said country.

It will thus be seen that my improved game will demand interest and attention 100 while being played, specially with children, and it is of such form that it can be manufactured and sold for advertising purposes with suitable displays thereon, if desired, while it can be manufactured cheaply and 105 will not take up any more room in packing or shipping than the ordinary fabric flag.

Various modifications and changes in the design, application, material and construction of my improved game may be resorted 110

to without departing from the spirit of the invention or sacrificing any of its advantages.

What I claim as my invention and desire

5 to secure by Letters-Patent is:—

1. A game apparatus comprising a sheet of material having red and white stripes and a blue field, said field having a star in the center of the same to represent the political center of the United States, and a series of 10 loose stars each representing one of the United States and adapted to be placed near to the star in said field by blindfolded players.

- 15 2. A game apparatus comprising a sheet

of material for the representation of an emblematic design, said sheet having a colored field and a star in the center of the same to represent the political center of a nation, and a series of loose stars each representing a political division and adapted to be placed near to the star in said field by blindfolded players. 20

In testimony whereof, I the said ISIDORE ROTHSTEIN have hereunto set my hand.

ISIDORE ROTHSTEIN.
